UNITED STATES PATENT OFFICE.

CHARLES A. HUNT, OF URBANA, ILLINOIS.

IMPROVED CLOTHES-DRIER.

Specification forming part of Letters Patent No. 35,684, dated June 24, 1862.

To all whom it may concern:

Be it known that I, CHARLES A. HUNT, of the city of Urbana, county of Champaign and State of Illinois, have invented a Clothes Drier with Peculiar Hinge Construction, of which the following is a description, reference being had to the accompanying drawings, and to the letters of reference marked thereon, in which—

Figure 1 is a top view, Fig. 2, a front elevation, and Fig. 3 a side elevation, of wings.

My clothes-horse may be either fixed to a wall in a sliding bar, C, or stand upon a pedestal with cast-iron feet.

The essential parts of the machine, aside from the upright fastenings, consist of a heel-hinge, D, which has its attachments or bearings upon the pedestal, or on the slide-bar C, and is designed to support a box-hinge, E, which plies between its jaws and swings laterally upon a rivet-axle. The hinge E, which attaches as above, is a box which opens out from the pedestal or slide-bar C, having pro-

jecting lips, between which wooden fingers A are fixed by rivets passing through their ends and through the lips, leaving the fingers A with free motion laterally, so they can open and close. The fingers A are of wood and some four feet long, upon which the clothing is designed to be hung for drying. The hinges are of cast-iron, and thus adapted to give not only free motion to the fingers, but a lateral motion to all at the same time, so that when not in use it can be entirely closed up and lie flat against the wall of a room.

What I claim, and desire to secure by Letters Patent, is—

The combination of the pedestal or slide-bar C with the hinges D E and fingers A, arranged and operating substantially as and for the purposes specified.

CHARLES A. HUNT.
